GRASS CATCHER ATTACHMENT FOR ROTARY MOWERS

Milo Nance and Blaine M. Nance, both of
1201 W. 1st. Ave., Kennewick, Wash.

Filed May 9, 1960, Ser. No. 60,495

Term of patent 7 years

(Cl. D40—1)

Fig. 1

Fig. 2

Fig. 3

Fig. 4

Fig. 5

FIG. 1 is a perspective view taken from the left side and rear of a grass catcher attachment for rotary mowers embodying our new design;

FIG. 2 is a right side elevational view thereof;

FIG. 3 is a rear elevational view thereof;

FIG. 4 is a front elevational view thereof; and

FIG. 5 is a top plan view thereof.

We claim:

The ornamental design for a grass catcher attachment for rotary mowers, as shown.
